UNITED STATES PATENT OFFICE.

DAVID I. BROWN, OF CINCINNATI, OHIO.

SWING.

1,363,453.

Specification of Letters Patent. Patented Dec. 28, 1920.

Application filed March 19, 1920. Serial No. 367,097.

To all whom it may concern:

Be it known that I, DAVID I. BROWN, a citizen of the United States, residing at Cincinnati, in the county of Hamilton and State 5 of Ohio, have invented certain new and useful Improvements in Swings, of which the following is a specification.

This invention relates to swings, and has for its general object to produce a novel 10 and improved swing wherein an improved suspension structure is provided to regulate the path of travel thereof and to prevent its undue tilting, twisting or lateral motion from its main plane of travel.

Another object of the invention resides in 15 a swing wherein the suspension structure is formed to embody a pair of parallel cable members whose upper ends are designed for swinging connection with a stationary support, the lower ends of said cable members being connected with a suitable form of seat 20 structure which is so formed as to cause a swing to travel in a plane longitudinal therewith, one of said cable members having its upper end connected with a swinging arm which has its upper end connected 25 with the stationary support on the same horizontal plane as the connection between the other cable member and the stationary 30 member, the lower end of said arm being movably connected with one of the cable members, this arrangement of parts being such that when the swing is moving in its proper longitudinal direction the cable 35 members are swinging from the same horizontal plane, but in the event of lateral movement on the part of the seat structure, the cables will be caused to swing from different planes, thus causing the seat structure 40 to quickly assume its normal path of movement so as to effectively prevent such undue travel.

Other objects reside in an improved swing 45 of economical and simple construction, capable of being readily erected and designed to furnish considerable amusement and pleasure to those using the same.

For a more complete understanding of the invention, reference is to be had to the 50 following description and to the accompanying drawing, wherein—

Figure 1 is a perspective view of the swing comprising the preferred form of the present invention, and

Fig. 2 is a detail sectional view of the hinge structure thereof.

The improved swing comprising the present invention consists in its preferred form of a seat structure 1, a plurality of supporting cables 2 and 3 and a stationary support 4, which latter may be in the form of a portable roof, a stationary beam or any equivalent structure.

In this instance the support 4 is provided with a rigid hook 5 from which the cable 6 depends. Preferably, this cable is in the nature of a chain and the upper link of which may be detachably connected with the hook 5 so as to provide a swinging support for the seat structure. The cable 3 70 extends approximately the full height of the swing and is provided contiguous to its lower end with a coil spring 6 by means of which the seat structure is rendered more or less resilient and the use of the swing is 75 thereby rendered more comfortable than if a rigid connection were to be employed. The extreme lower end of the cable 3 is provided with an eye 7, which engages with the hooked forward end 8 of the seat structure 1. The latter is preferably formed so as to provide an enlarged seat portion 9 and a reduced forward portion 10, the construction of the seat being such that the limbs of the user may freely extend downwardly so as to effect the propulsion of the swing. A back rest 11 is provided upon the rear end of the seat structure by means of hook bars 12, with which the divided lower ends 13 of the cable 2 are secured. 80 These ends converge upwardly and are joined to the main body of the cable 2 by means of the S link 14. By means of this divided construction of the cable 2 a non-tiltable support for the seat structure is 85 provided.

The upper end of the cable 2 is connected with the lower hooked end 15 of a swinging arm 16, said arm being so arranged as to lie co-extensively with the upper end of the cable 3. The upper end of the arm is pivotally connected as at 17 with a metallic bracket 18 carried by the stationary support 4.

From the foregoing it will be observed 105 that when the seat structure is traveling in its normal longitudinal plane, its cables will swing from a common horizontal plane, this being caused by placing the pivot 17 on substantially the same horizontal plane as the 110 hook 5. This arrangement causes the cables to oscillate in parallelism. However, in the

event of lateral movement on the part of the seat structure it will be manifest that the cables will oscillate from different horizontal planes, that is, the arc of swinging movement of the front cable will be greater than that of the rear cable 2, since the latter when moving laterally will oscillate from the hook 15 formed on the lower end of the arm 16. Manifestly, the connection between the 10 upper end of the arm 16 and the bracket 18 will not admit of lateral swinging movement. Therefore, by the provision of the structure described a swing is provided which is freely movable in a longitudinal 15 plane only and therefore any undue lateral movement on the part of the seat structure will be readily taken care of and prevented by the cable suspension. All of this construction contributes toward a swing whose 20 construction is simple and free to manipulate and yet may be safely used by children without liability of accident. The swing as will be manifest, is of staunch and simple construction, may be cheaply manufactured 25 and possesses attractive and pleasing outlines.

What is claimed is:

1. A swing comprising a seat structure, a pair of cables connected to the opposite longitudinal ends of said structure, one of said cables being directly connected for swinging movement with a main stationary support, the other of said cables having its upper end similarly connected with a hinged 30 member pivotally carried by said support, said member lying in parallelism with said cables and operating to permit said cables to swing from the same horizontal plane when the swing is moving longitudinally 35 but from different horizontal planes upon 40 lateral movement of the swing.

2. A swing comprising a pair of spaced parallel cables, a seat structure secured to the lower ends of said cables, and means cooperative with the upper ends of said cables 45 to permit the latter to swing on substantially the same horizontal plane upon longitudinal movement of the seat structure but on different horizontal planes upon lateral movement of said seat structure. 50

3. A swing comprising a pair of spaced cables, a connection between the upper end of one of said cables and a stationary support, an arm pivotally movable in the longitudinal plane of said swing, the lower end 55 of said arm being connected with the upper end of the other of said cables, and a seat structure carried by the lower ends of said cables, said arms serving to permit said cables to swing from substantially the same 60 horizontal plane when the swing is moved longitudinally but from different horizontal planes upon lateral movement on the part of the swing.

4. A swing comprising a seat structure including a back rest and a reduced forward extremity, a cable having its upper end adapted for connection with a supporting member, the lower end of said cable being secured to the forward reduced portion of 70 said seat structure, a second cable having a divided lower portion secured to the back rest of said seat structure, a hinged arm pivoted to said supporting member on substantially the same horizontal plane as the 75 connection between said supporting member and the upper end of said first named cable, and the lower end of said arm being connected with the upper end of said second cable. 80

In testimony whereof I affix my signature.
DAVID I. BROWN.
